Inventor:

UNITED STATES PATENT OFFICE.

WILLIAM J. INFIELD, OF SAN FRANCISCO, CALIFORNIA.

RAIL AND RAILWAY-CROSSING.

1,145,142.

Specification of Letters Patent.

Patented July 6, 1915.

Application filed December 18, 1914. Serial No. 877,959.

To all whom it may concern:

Be it known that I, WILLIAM J. INFIELD, citizen of the United States, residing at San Francisco, in the county of San Francisco and State of California, have invented certain new and useful Improvements in Rails and Railway-Crossings, of which the following is a specification, reference being had therein to the accompanying drawing.

10 This invention relates to rails and railway crossings, of a character more especially designed for use in connection with car wheels having flangeless treads.

One of the primary objects of the invention is to provide a rail and rail crossing in which the tread of the car wheel is adapted to engage a relatively flat surface of the rail, and said rail having at opposite sides flanges, adapted to overlie for a considerable distance the sides of the car wheel, to the end that the car wheels in passing over the rail and through the crossing, will travel in a continued uniform plane.

By the present invention, it is designed 25 to overcome the usual pounding, jolting and incident noise in the passage of the rimmed wheels of usual construction over the crossing and thereby prolong the life of the crossing.

30 It is a further object of the invention to provide a rail and crossing of improved construction, the rails being constructed so as to have oppositely disposed flanges of substantially equal depth, thereby overcoming 35 to a large extent the spreading of the rails and derailing of the cars.

Still further, the invention includes a rail and crossing, of simple construction, cheap to manufacture, strong and durable, and 40 highly efficient in operation.

In the drawings:—Figure 1 is a transverse sectional view taken on the line 1—1 of Fig. 2, and showing a pair of the improved rails with a pair of the improved 45 car wheels in coöperative relation with the rails; Fig. 2 is a plan view of the crossing and connecting rails; Fig. 3 is a cross sectional view of one of the improved rails, taken substantially on the line 3—3 of Fig. 2.

50 With more particular reference to the drawings, wherein like reference numerals refer to corresponding parts throughout the several views, the improved type of rail is preferably constructed, substantially as follows:

1 is a base flange, preferably having a flat

under surface adapted to engage the cross ties or sleepers of wood, or other suitable material, and 2 is a vertically extending web arranged substantially midway of the 60 sides of the base 1, and connecting with said base 1, the upper surface of which latter inclines downwardly and outwardly, as indicated at 3, from opposite sides of the web 2 to the outer edge of the base 1. The head 65 of the rail projects at opposite sides beyond the sides of the vertical web 2 and is substantially U-shaped in cross section, whereby to provide a relatively wide flat tread surface, 4, and relatively deep side flanges 5. 70 These side flanges 5 are preferably of the same depth, and of like construction, and are designed to overlie the sides of the wheel for a considerable distance, whereby to prevent accidental derailment and to provide 75 a smooth running surface.

The inner surface of the side rims or flanges 5 taper slightly inwardly toward the base, as indicated at 6, whereas the outer surfaces 7, of said side flanges, gradually 80 curve inwardly from a point adjacent the tread portion 4, to their point of connection with the web 2 a considerable distance below the tread portion 4, to the end that the side flanges 5 are considerably reinforced 85 against lateral strains by the web portion 2 of the rails.

It is to be understood that the present construction of rail is designed more particularly for use in connection with car wheels 90 devoid of side rims or flanges, as illustrated at 8, in Fig. 1, with the result that the continuous smooth tread or periphery of the wheels will lie flat upon the tread surface 4.

The crossing to be now described is also 95 of a construction adapted more particularly for rimless tread wheels, and the rail portions of the crossing are of a construction to constitute, in effect, continuations of the rails connected therewith, with the result 100 that the car wheels, in passing from the rails onto and over the crossing, will be devoid of the usual jar and pounding in passing from one part to the other.

The crossing is provided with a wheel engaging surface 9 which said surface is in substantially the same horizontal plane with the wheel engaging surface 4 of the connecting rails. The said surface 9 has projecting upwardly therefrom suitable flanges adapted 105 to overlie the sides of the car wheel, and thereby constitute in effect continuations of 110

the side flanges 5 of the rails. These flanges are so conveniently of the following construction:—10 is a substantially rectangular flange; 11 substantially U-shaped flanges, 5 and 12 V-shaped flanges. These flanges are spaced one from the other whereby they form, in the crossing, the intersecting runways of the crossing.

The wheel engaging surface 9 of the crossing is suitably supported upon a base or body-part 13, and those portions of the surface 9 overlaid on one side by one arm of the U-shaped flange, and at an opposite side by one arm of the V-shaped flange 12, 15 project outwardly beyond the body portion 13, so as to constitute an extended rail member of substantially the same construction as the rail members hereinbefore first described. These outward rail extensions of 20 the crossing have a downwardly projecting central web 14, connecting with a suitable base 15, and reinforcing portions 16 are arranged between the under surface of the rail extensions of the crossing and the upper 25 surface of the base 15, at the point of connection of the web portion of the said extension with the body portion of the crossing.

It will be understood that the flanges of 30 the crossing which form therebetween intersecting runways for the car wheels are of substantially the same design and construction as the flanges of the rails, and of preferably the same depth, to the end that the car 35 wheels in passing from the rail section into the crossing will be maintained in the same horizontal plane, and thereby overcome the usual pounding and jarring at present manifest in constructions wherein the car wheel 40 must pass from one horizontal plane to the other, passing onto or from a crossing.

It will be appreciated that the various portions of the crossing including the body part, the flanges which overlie the wheel en-

gaging surfaces, the integral rail projections, and the reinforcing means for the webs may be and preferably are of integral construction throughout, as illustrated.

I claim:—

1. In an integral rail, the combination of 50 a base portion, a head portion having a flat upper surface adapted to be engaged by the periphery of a car wheel, a web connecting the head and base portions, said web being arranged substantially midway of the sides 55 of the head and base portion, and side flanges projecting upwardly from the side edges of the flat wheel engaging surface of the head, said side flanges being of a height to overlie a substantial portion of the opposite sides of the wheel and the inner surfaces of said flanges inclining outwardly toward the upper edge thereof.

2. In a railway construction, the combination 60 of a crossing having a flat wheel engaging surface and flanges projecting upwardly from the side edges of said surface whereby to divide the crossing into intersecting runways, and integral rail extensions for said crossing one for each runway, said rail extensions comprising a base part, a head part, and a connecting web part, said head part having a flat wheel engaging surface in horizontal alignment with the wheel engaging portion of the crossing, and side flanges to 75 overlie the sides of the wheel in vertical alignment with the side flanges of the crossing runways, the inner surface of said side flanges of the rail extensions and the crossing tapering from the point of connection 80 with the flat wheel engaging surface to the upper edge of said flanges.

In testimony whereof I affix my signature in presence of two witnesses.

WILLIAM J. INFIELD.
